UNITED STATES PATENT OFFICE.

HARRY ALBERT GRIFFITHS, OF EDGECASTON, BIRMINGHAM, AND RICHARD HANSON GRIFFITHS, OF SUTTON COLDFIELD, ENGLAND.

SHEET-METAL-WORKING MACHINE.

1,382,974.

Specification of Letters Patent. Patented June 28, 1921.

Application filed March 23, 1921. Serial No. 454,832.

(GRANTED UNDER THE PROVISIONS OF THE ACT OF MARCH 3, 1921, 41 STAT. L., 1313.)

To all whom it may concern:

Be it known that we, HARRY ALBERT GRIFFITHS, residing at 8 Chad road, Edgbaston, in the city of Birmingham, England, and 5 RICHARD HANSON GRIFFITHS, residing at "Highfield," Sutton Coldfield, in the county of Warwick, England, subjects of the King of Great Britain and Ireland, have invented 10 certain new and useful Improvements Relating to Sheet-Metal-Working Machines, for which we have filed application in England, August 26, 1919, of which the following is a specification.

This invention relates to sheet metal 15 working machines, such as cutting, drawing, embossing and like presses, and has for its object to provide improved means for automatically feeding the sheet metal blanks to the tools.

20 The invention comprises the combination with a blank holder in which a stack of blanks are placed, of knife edge wedges or separating tools rotatable in a plane parallel with those of the blanks and adapted 25 when rotated to enter between the bottom blank and those above it, together with means for lifting the separating tools so that the stack of blanks is raised clear of the bottom blank and the latter is left free 30 to fall down an inclined chute by gravity or be pushed out by any suitable mechanical device.

Referring to the six accompanying sheets of explanatory drawings:—

35 Figure 1 is a plan, Fig. 2 an end view and Fig. 3 a cross section on 1—2, Fig. 1, of an automatic feeding device constructed in accordance with this invention.

40 Fig. 4 is a plan of a cam for lifting one of the separating tools and Fig. 5 is a plan of one of the separating tools.

Figs. 6, 7 and 8 are diagrammatic views 45 illustrating stages in the operation of one of the separating tools used in the mechanism shown in Figs. 1—5.

Fig. 9 is a plan, and Fig. 10 an end view of a modified form of our automatic feeding mechanism.

Fig. 11 is a cross section through the holding and separating elements in the plane of the line 3—4 Fig. 9.

Figs. 12, 13 and 14 are diagrammatic

views illustrating stages in the operation of the mechanism shown in Figs. 9—11.

The same reference letters in the different 55 views indicate the same or similar parts.

In carrying the invention into effect as shown in Figs. 1—8 an annular blank holder *a* for containing circular blanks is mounted on a chute *b* which is arranged in an inclined position in front of the cutting or shaping tools of the machine. The lower or fixed tool is indicated by *c*. Above the holder project a pair of pins *d* for supporting those blanks in the stack which are 60

not contained within the ring *a*. At diametrically opposite sides of the holder are arranged a pair of eccentric rotatable knife edge wedges or separating tools *e* which when rotated can enter between the bottom 70

blank and those above it sufficiently to separate the bottom blank and support the others. On each spindle *f* which carries the separating tool at its upper end, is arranged a collar *g* adapted by means of a lateral 75

projection *h* to engage a stationary cam *i*. Each separating tool can also engage the holder through the medium of a piece *j* for the purpose of lifting the holder. The holder is arranged to move vertically on 80

guide stems *k* against the action of springs *l*. After the separating tools have been rotated into engagement with the stack of 85

blanks, further rotation causes the said collar by its engagement with the cam, to lift the separating tools and at the same time to 90

lift also the stack of blanks and the holder, leaving the bottom blank free. As the underside of the holder is now clear of the chute *b* the bottom blank can slide down 95

the chute by gravity toward the tools. The operation of the mechanism is afterward reversed, the holder and blanks being lowered to the original position and the separating tools withdrawn from the blanks prior to a 95

repetition of the sequence of operations. The two spindles *f* of the separating tools are connected for simultaneous operation by a link *m* acting on levers *n* at the lower ends of the spindles, and any convenient provision is made for actuating the spindles automatically from the crank shaft or other moving part of the press at the proper intervals during the operations of the tools. 100

In the drawings the link *m* is shown connected to a lever *o* on a shaft *p* which is actuated as above mentioned. A small amount of free endwise movement is arranged in the spindles *f* of the separating tools and these are held down by springs *g*. The holder is returned after the lifting movement by the springs *l*.

Referring to Figs. 6-8 the blanks as indicated by *r* lie initially within the holder as shown in Fig. 6. Only a few blanks are shown. It will be understood that the stack of superimposed blanks may contain any convenient number, new blanks being intermittently placed on the top of the stack while the lower ones are being removed by the mechanism. The distance of the operative edge of the separating tool *e* above the upper surface of the chute on which the blanks are supported is equal to the thickness of a single blank. In Figs. 6-8 only one separating tool is shown; there is another like tool at the opposite side of the blank as shown in Figs. 1-3. During the first part of the rotation of the spindle *f*, the separating tool enters between the bottom blank and the remainder and comes into contact with the part *j* of the holder as shown in Fig. 7. Further rotation of the spindle causes the cam like projection *h* of the collar *g* to engage the fixed cam *i*, and the interaction of the parts *h* and *i* causes the spindle to rise. The separating tool thereupon lifts the upper blanks and the holder as shown in Fig. 8, leaving the bottom blank free to slide under the holder by gravity to the feeding tools.

During the transit of the blanks from the holder to the tools, each is preferably held in turn by an automatic stop *s* (Fig. 1) beneath an oiling pad which is brought into contact with the blanks by means actuated in conjunction with the tools. The oiling pad is not shown but its position is indicated by dotted lines *t* (Fig. 1). On withdrawing the stop the blank completes its advance and is arrested by stops *u* at the proper position between the tools. After the shaping, cutting or other operation, the blanks are ejected in any usual manner. In Fig. 1 a blank *r* is shown resting against the stops *u* in position over the fixed or bottom tool *c*. The stop *s* is actuated at the proper intervals automatically by a link *v* attached to a lever *w* on the shaft *p*.

Referring to the mechanism shown in Figs. 9-11, the blank holder is formed by a pair of pins *a* secured to the base or chute *b* and a vertically movable stem *a'* which is held down by a spring blade *l*. The pin *a'* is guided by a bridge piece *x*. Instead of two separating tools *e* acting simultaneously on opposite sides of the blanks, a single tool *e* is arranged to produce the preliminary separation of the blanks at one side only, and

adjacent to this is arranged a larger scythe like separating tool *e'* which can pass into the space produced by the tool *e* and complete the lifting of the blanks.

The tool *e* is attached to a spindle *f* provided with a projection *h* which can coact with a fixed cam *i*. Rotation of the spindle is effected by a link *m* connected to a lever *n* on the spindle and also to a lever *o* on the shaft *p*. Likewise the spindle *f'* of the tool *e'* is provided with a projection *h'* coacting with a fixed cam *i'*. The tool *e'* is actuated by a link *m'* connected to a lever *o'* on the shaft *p*. Both tools are held down by blade springs *g* *g'* acting on the spindles *f* *f'* respectively.

The tool *e'* is also adapted to lift the holder element *a'*, the latter being chamfered on its rear side (Fig. 11) to permit of the tool *e'* sliding beneath it.

The action of the mechanism will readily be followed by reference to Figs. 12-14. Initially the tools occupy the relative positions shown in Figs. 9 and 12 from the latter of which the blanks have been omitted for clearance of illustration. The tool *e* first comes into operation and separates the upper blanks *r* at one side from the lower blank as shown in Fig. 13, sufficiently to permit the subsequent entry of the tool *e'*. This now comes into action, and by passing between the blanks lifts the upper ones from the bottom blank. It also lifts the holder element *a'*, and due to the interaction of the parts *h'* and *i'*, the blanks *r* and the holder element *a'*, are raised completely clear of the bottom blank as shown in Fig. 14. During the lifting of the tool *e'* by the parts *h'* *i'* the tool *e* is also lifted by the interaction of the parts *h* *i*. The bottom blank is thus permitted to pass to the next position as already described in connection with the mechanism shown in Figs. 1-3. Subsequently the separating tools are returned, and the cycle of operations is repeated.

On its passage to the tools the liberated or discharged bottom blank may be arrested by a stop *s* to permit of an oiling operation by a lubricating pad *t* as already described.

By means of this invention it is only necessary for the attendant to maintain the supply of blanks in the holder, the feeding forward of each bottom blank in turn being effected automatically.

In some cases any convenient provision is made for pushing the blanks forward by mechanical means instead of allowing them to slide down the chute by gravity as above described.

To prevent derangement or damage due to two blanks passing out of the holder simultaneously, the blanks may be caused to pass over a balance before reaching the tools. Provision would then be made so that two blanks would tilt the balance and cause

the feeding forward of the blanks to be arrested.

Having thus described our invention what we claim as new and desire to secure by Letters Patent is:—

1. In mechanism for automatically feeding sheet metal blanks to the tools of cutting, drawing, embossing and like presses, the combination of a blank holder in which a stack of blanks is placed, rotatable knife edge separating tools adapted to enter between the bottom blank and those above it, and means for lifting the separating tools so that the stack of blanks is raised clear of the bottom blank and the latter is thereby released for transfer to the press tools, substantially as described.
2. In mechanisms for automatically feeding sheet metal blanks to the tools of cutting, drawing, embossing and like presses, the combination of a movable blank holder in which a stack of blanks is placed, rotatable knife edge separating tools adapted to enter between the bottom blank and those above it, and means for lifting the holder and the separating tools so that the stack of blanks is raised clear of the bottom blank and the latter is thereby released for transfer to the press tools, substantially as described.
3. In mechanisms for automatically feed-

ing sheet metal blanks to the tools of cutting, drawing, embossing and like presses, the combination of a movable holder in which a stack of blanks is placed, rotatable knife edge separating tools adapted to enter 35 between the bottom blank and those above it, means for lifting the separating tools so that the stack of blanks is raised clear of the bottom blank, and an inclined chute down which the released bottom blank can 40 slide to the press tools, substantially as described.

4. In mechanisms for automatically feeding sheet metal blanks to the tools of cutting, drawing, embossing and like presses, 45 the combination of a holder for a stack of blanks, a pair of rotatable knife edge separating tools one of which enters first between the bottom blank and those above it, the other then following into the aperture 50 thus made and serving as a support for the stack, and means for raising the stack through the medium of one or both of the separating tools, clear of the bottom blank, leaving the latter free for transfer to the 55 press tools, substantially as described.

In testimony whereof we have signed our names to this specification.

HARRY ALBERT GRIFFITHS.

RICHARD HANSON GRIFFITHS.
